UNITED STATES PATENT OFFICE.

SAMUEL B. VAN RANST, OF SYRACUSE, NEW YORK, ASSIGNOR TO CROUSE-HINDS COMPANY, OF SYRACUSE, NEW YORK, A CORPORATION OF NEW YORK.

LAMP-SHADE HOLDER.

1,076,848.

Specification of Letters Patent.

Patented Oct. 28, 1913.

Application filed October 6, 1910. Serial No. 585,603.

To all whom it may concern:

Be it known that I, SAMUEL B. VAN RANST, of Syracuse, in the county of Onondaga and State of New York, have invented 5 a new and useful Lamp-Shade Holder, of which the following is a specification.

My invention has for its object the production of a lamp shade holder adapted to be connected to incandescent lamp sockets, 10 and it consists in the combinations and constructions hereinafter set forth and claimed.

In describing this invention, reference is had to the accompanying drawing, in which like characters designate corresponding parts 15 in all the views.

Figure 1 is an elevation of my lamp shade holder attached to one form of an incandescent electric lamp socket. Fig. 2 is a view similar to Fig. 1 showing the operation 20 of the collar of the shade holder and contiguous parts when the shade holder is being sprung on the socket over the bead thereof. Fig. 3 is a plan of my lamp shade holder.

25 This lamp shade holder comprises a hollow body 1 having means as screws 2 at one end for engaging a lamp shade, the body also having three arms 3 intermediate of its ends and converging toward the axis of 30 the shade holder and spaced substantially equidistant apart, and an expansible and contractile collar 4 carried by said arms. Usually, the body is pressed from a single piece of sheet metal. The collar 4 is here 35 shown as divided midway between two of the arms 3, and the divisions thereof are provided with clamping means for contracting the collar on a socket 5, and the other two portions of the collar between arms 3 are 40 provided with means for increasing the elasticity of said portions and permitting the same to twist or distort during the expansion of said collar over the bead 6 of the lamp socket from its normal position, as 45 shown in Fig. 1 to the position shown in Fig. 2, and as here shown, this means comprises transverse crimps or corrugations 7 in two portions of the collar between arms 3. The crimps or corrugations 7 project out- 50 wardly from the contiguous portions of the collar 4 and hence the portions of the collar on opposite sides of the corrugations lie flatwise against the support as a lamp socket to which the holder is attached. Said cor- 55 rugations render the collar elastic in order

that it may be easily but not permanently distorted, without weakening the same and decreasing its capability of being firmly clamped on the lamp socket. The ends of the divided portion of the collar are bent 60 outwardly forming ears 8 which are perforated, and the perforation of one of said ears is threaded and that of the other unprovided with threads, and a clamping screw 9 extends through said perforations for contracting the collar upon the lamp socket. Preferably, the portions of the collar between the arms 3 are compressed inwardly 65 into arcs of less radii than the normal radius of the collar, that is, the radius of the 70 arc of any one of the parts 10 joined to the upper ends of the arms 3. The corrugations or crimps 7 are usually formed in the compressed portions and take up the surplus metal due to the compressing of two of such 75 portions into the arcs of less radii, in addition to rendering the collar elastic so that it may be readily sprung over the beads of lamp sockets without permanent distortion. The compressing inwardly of portions of 80 the collar also provides bearing surfaces spaced apart at intervals around the collar, for engaging the lamp socket.

Heretofore, lamp shade holders made of one piece of sheet metal have had but two 85 arms supporting the clamping collar in order that the collar could be sprung onto the sockets over the beads thereof without twisting, warping or stretching the collar, and in most instances two arms are inadequate to properly make a rigid structure and support a lamp shade. However, where 90 more than two arms are provided and the collar is forced to expand over the bead of a lamp socket, the undivided portions of 95 such collar are twisted and stretched out of shape during the expansion of the collar over the bead of the lamp socket owing to the fact that the ends of the two arms nearest the line of division of the collar have a 100 greater movement outwardly or radially during such expansion than the third arm. Oftentimes, when more than two arms are used the collar and arms have been connected by pins which fit loosely in order to permit of a limited amount of play between the collar and arms during the expansion of the collar over the bead of the socket. Such twisting or distortion of the portions of the 105 collar is undesirable, renders the collar 110

weak, and oftentimes the distortion is permanent so that the collar does not spring back to its original form. Owing to the transverse corrugations or crumps 7 of the collar 4, such twisting and distortion is permitted without weakening the collar, and while the collar is being expanded over the bead of the socket, the crimps or corrugations 7 of the undivided portions between the arms 3 permit distortion of the collar without liability of injuring the same.

What I claim, is:—

1. A lamp shade holder comprising a body having means for engaging a lamp shade, 15 arms spaced apart intermediate of its ends, an expandible and contractile collar for engaging a support, the collar being carried by the arms, and a portion of the collar between the arms being compressed into an 20 arc of less radius than the normal radius of the collar, and said portion being formed with a transverse corrugation projecting outwardly, a portion of the collar unprovided with a corrugation being split, and 25 clamping means coacting with the collar on opposite sides of the split thereof, substantially as and for the purpose described.

2. A lamp shade holder comprising a body having means for engaging a lamp shade, 30 arms spaced apart intermediate of its ends, and an expandible and contractile collar for engaging an electric lamp socket, the collar being carried by the arms, and a portion of the collar being compressed into an arc of less radius than the normal radius of the 35 collar, substantially as and for the purpose set forth.

3. A lamp shade holder comprising a body having means for engaging a lamp shade, 40 arms spaced apart intermediate of its ends, and an expandible and contractile collar for engaging an electric lamp socket, the collar being carried by the arms, and portions of the collar spaced apart being compressed 45 into arcs of less radii than the normal radius of the collar, substantially as and for the purpose described.

4. A lamp shade holder comprising a body having means for supporting a lamp shade, 50 arms spaced apart intermediate of its ends, and an expandible and contractile collar for engaging an electric lamp socket, the collar being carried by the ends of the arms and being fixed thereto, the portions of the collar 55 between the arms being compressed inwardly and located in arcs of less radii than the radii of the arcs in which are located the parts of the collar joined to the ends of the arms, and means for contracting the 60 collar on such socket, substantially as and for the purpose specified.

5. A lamp shade holder comprising a body

having means for supporting a lamp shade, arms spaced apart intermediate of its ends, and an expandible and contractile collar for 65 engaging an electric lamp socket, the collar being carried by the ends of the arms and being fixed thereto, the portions of the collar between the arms being compressed and located in arcs of less radii than the radii of 70 the arcs in which are located the parts of the collar joined to the ends of the arms, and the compressed portions of the collar being formed with means rendering the same elastic and permitting said compressed 75 portions to twist during the expanding of the collar on the lamp socket, substantially as and for the purpose set forth.

6. A lamp shade holder comprising a body having means for supporting a lamp shade, 80 arms spaced apart intermediate of its ends, and an expandible and contractile collar for engaging an electric lamp socket, the collar being carried by the ends of the arms and secured thereto, the portions of the collar 85 between the arms being compressed and located in arcs of less radii than the radii of the arcs in which are located the parts of the collar joined to the ends of the arms, and said portions between the arms being 90 formed with transversely extending corrugations projecting outwardly, and means for contracting the collar on such socket, substantially as and for the purpose described.

7. A lamp shade holder comprising a body 95 having means at one end for supporting a lamp shade, three arms spaced equidistant apart intermediate of its ends, and an expandible and contractile collar for engaging an electric lamp socket, the collar being 100 formed integral with the arms and portions of the collar between the arms being compressed and located in arcs of less radii than the radii of the arcs in which are located the parts of the collar joined to the arms, and two of said portions being formed with 105 transversely extending corrugations projecting outwardly, the third of such portions of the collar located between said arms being divided transversely, and the ends thereof terminating at the line of division being bent outwardly forming ears, and clamping means coacting with the ears for contracting the 110 collar on such socket, substantially as and for the purpose specified.

In testimony whereof, I have hereunto signed my name in the presence of two attesting witnesses, at Syracuse, in the county of Onondaga, in the State of New York, this 30th day of September, 1910.

SAMUEL B. VAN RANST.
